UNITED STATES PATENT OFFICE.

ARTHUR KITSON, OF PHILADELPHIA, PENNSYLVANIA, ASSIGNOR TO THE
KITSON HYDROCARBON HEATING AND INCANDESCENT LIGHTING COMPANY,
OF SAME PLACE AND CHARLESTON, WEST VIRGINIA.

VAPORIZING APPARATUS.

SPECIFICATION forming part of Letters Patent No. 665,109, dated January 1, 1901.

Application filed April 24, 1899. Serial No. 714,183. (No model.)

To all whom it may concern:

Be it known that I, ARTHUR KITSON, a subject of the Queen of Great Britain, and a resident of Philadelphia, county of Philadelphia, 5 State of Pennsylvania, have invented certain new and useful Improvements in Vapor-Burning Apparatus, of which the following is a specification.

My invention relates to vapor-burning apparatus, and is more specifically designed to produce an improved form of single-burner apparatus for burning the vapor of kerosene or other fluid hydrocarbon mixed with air under the ordinary form of incandescent mantle.

The preferred form of my apparatus is illustrated in the accompanying sheet of drawings, in which—

Figure 1 is an elevation and partial section of my apparatus. Fig. 2 is a detail section 20 showing a union connecting the U-shaped vaporizing-tube to its supporting-tubes.

Throughout the drawings like reference figures refer to like parts.

The lamp is preferably mounted on a reservoir or bowl (not shown) containing oil and compressed air, it being secured into said bowl by the threaded nipple 1. A valve 2 controls the flow of oil from the bowl through the oil-supply tube 3 to the vaporizing-tube 4, which is preferably made in the shape of a U or horseshoe, so as to extend up along-side of and across the top of the incandescent mantle 20, said incandescent mantle being supported from the vaporizing-tube by the wire 21 or other convenient means. 23 is a short chimney mounted on the upper portion of the vaporizing-tube, and 22 is a drip-valve in the lower part of the burner apparatus.

This burner and air-mixing apparatus are all 40 mounted on or within the upright tube 5. The vapor is carried from the end of the vaporizing-tube by the vapor-discharge tube 6, which is preferably bent to one side and has an outwardly-flaring discharge-opening 7, formed by punching up a portion of the wall of the tube. The bent portion of this vapor-discharge tube extends across the mouth of the short mixing-tube 8 and discharges downward through said mixing-tube. The mixing-tube extends into the globular extension

9 on the lower end of the main upright tube 5 and discharges down toward the bottom or closed end of said globular extension. The vibrating arm 10 is pivoted on the end of the vapor-discharge tube 6 at the point 6^a. This 55 arm carries a needle 10^a on its inner ends adapted to enter the opening 7 in the vapor-discharge tube when the operator pulls down on the chain 11, attached to the outer end of the vibrating lever 10.

12 represents the burner proper, which is formed by contracting the upper end of the main tube 5 or by inserting a thimble therein. The gauze 13 is placed over the burner-opening and held in place by the annular 65 cap 14. A second lower gauze 15 may be inserted in the burner. A metal collar 16 is placed on the upper end of the tube 5 and surrounds the burner 12, leaving an annular space between the two. This collar, as 70 shown, is in metallic contact with the tube 5, and the particular construction shown might be varied, so long as any construction was employed which gave free conduction of heat from the collar 16 to the body of the tube 5. 75

The U-shaped vaporizing-tube 4 is connected to the oil-supply tube 3 and the vapor-discharge tube 6, which are located on opposite sides of the burner, by means of the unions 17 17^a, and between the abutting ends 80 of the tubes I preferably introduce gauze diaphragms 19, as shown. In the vaporizing-tube is a U-shaped rod or wire 18, which is preferably supported in position by the wire-gauze diaphragms.

The upper ends of the oil-supply tube 3 and the vapor-discharge 6 are supported in any convenient way, as by the yoke 24.

The method of operating my invention is as follows: The vaporizing-tube 4 being heated 90 by a gasolene-torch or any other convenient means of preheating, (not shown,) the valve 2 is opened and the oil is forced up through the supply-pipe 3 and the gauze diaphragm 19 into the vaporizing-tube 4. As it passes up 95 and over the mantle through this vaporizing-tube it is compelled by the internal filler 18 to pass along the surface of the tube in a comparatively thin layer or film, and is thus brought in thorough contact with the hot 100

tube. By the time it has approached the union 17^a it is in the form of vapor, which passes through the diaphragm, through the vapor-discharge tube 6, and out at the discharge-opening 7 in the form of a jet. This jet passes down the mixing-tube 8, drawing in the necessary quantity of air. The noise of the jet may be muffled and suppressed by any form of muffler. (Not shown.) The mixture of vapor and air is discharged into the lower globular end 9 of the upright tube 5 and there compelled to reverse its direction of flow and pass up through the main tube 5 to the burner, where it is ignited and burns under the incandescent mantle 20, heating the U-shaped vaporizing-tube. By pulling on the chain 11 the needle 10^a can be projected up into the opening 7, when the same has become clogged by the accumulation of carbon, cleanses the opening, and enables the lamp to continue in operation. The radiated heat of the burner and mantle strikes the vertical portions of the U-shaped vaporizing-tube 4, and the upward-flowing current of hot gases is concentrated on the upper portion of the tube by the chimney 23.

The advantages of my invention consist in the fact that the mixing operation is all done within the short tube 5, which is kept hot by the fact of its metallic connection with the burner 12 and the surrounding collar 16. The lower skirts of the mantle 20 are of course kept hot by conduction from the upper portions, which are in the immediate vicinity of the flame, and heat radiated from this lower skirt of the mantle is intercepted by the metallic collar 16. The oil-supply tube is also carried up partly through this upright tube 5 and bathed in the current of hot vapor and air within the same.

It is evident, of course, that various changes could be made in the details of construction illustrated without departing from the spirit and scope of my invention, so long as the rela-

tive arrangement of parts shown in the drawings or the principle of operation set out in the specification is preserved. Thus the position of the oil-supply tube 3 might be varied, as indicated in dotted lines, other forms of burner might be employed, various devices for muffling the hissing noise of the jet might be added, &c.; but all these I consider matters of form and not of substance and regard the resulting apparatus as still within the scope of my invention.

The form, construction, and connections of, for example, the oil and vapor tubing, the chimney, the burner, &c., herein shown and described are not specifically claimed, for the reason that such features combined in various ways constitute the subject-matter of other applications now pending.

Having therefore described my invention, what I claim as new, and desire to protect by Letters Patent, is—

1. In a vapor-burning apparatus the combination of the upright tube having an enlarged globular portion at its lower end, the burner at the upper end of the tube, the mixing-tube angularly disposed to the upright tube and discharging into the globular portion thereof, and the vaporizing-tube within the heating zone of the burner and discharging into the outer end of the mixing-tube.

2. In a vapor-burning apparatus the combination of the mixing-tube, the vapor-discharging tube extending across the mouth of the mixing-tube and having a discharge-opening in its side, and the needle-carrying arm pivoted on the end of the vapor-discharge tube, and so disposed as to swing the needle through the discharge-orifice.

Signed by me at New York city, New York, this 22d day of April, 1899.

ARTHUR KITSON.
